ELECTRIC KNIFE HANDLE

Clarence L. Folden, Downers Grove, Ill., assignor to
Sears, Roebuck and Co., Chicago, Ill., a corporation
of New York

Filed Nov. 2, 1964, Ser. No. 82,422

Term of patent 7 years

(Cl. D22—3)

FIG. 1 is a perspective view of an electric knife handle, showing my new design;

FIG. 2 is a side elevational view of same, on an enlarged scale;

FIG. 3 is a top plan view thereof;

FIG. 4 is a bottom plan view thereof;

FIG. 5 is a rear elevational view of same;

FIG. 6 is a front elevational view thereof, and

FIG. 7 is a fragmentary sectional view substantially along line 7—7 of FIG. 3.

The fragmentary broken-line showing of the knife blade in FIGS. 1-4, inclusive, is for purposes of illustration only.

1 claim:

The ornamental design for an electric knife handle, substantially as shown and described.
